WRITING INSTRUMENT

Hans Reinhard Fehling, Zug, Switzerland, and Alfred Dennis Street, Pinner, England, assignors to I.R.C. Limited, London, England, a company of Great Britain

Continuation of design applications Ser. Nos. 73,843 and 73,844, Mar. 6, 1963. This application Dec. 15, 1964, Ser. No. 83,117

Term of patent 14 years

(Cl. D74—17)

FIG. 1 is a side view of a writing instrument showing our new design, the side opposite thereto being a mirror image thereof;

FIG. 2 is a similar side view thereof as it appears with the writing point in projected position;

FIG. 3 is a front view of the writing instrument as disclosed in FIG. 1; and

FIG. 4 is a similar front view of the writing instrument as disclosed in FIG. 2;

FIG. 5 is a side view of another embodiment of the writing instrument shown in FIG. 1 wherein a clip and a slight curvature have been applied to the barrel portion, the side opposite thereto being a mirror image thereof;

FIG. 6 is a similar side view thereof as it appears with the writing point in projected position;

FIG. 7 is a front view of the writing instrument as disclosed in FIG. 5; and

FIG. 8 is a similar front view of the writing instrument as disclosed in FIG. 6.

This is a continuation of our applications Ser. No. D. 73,843 and Ser. No. D. 73,844 both filed on Mar. 6, 1963, and now abandoned.

We claim:

The ornamental design for a writing instrument, as shown and described.
